WATER CLOSET BOWL WITH INTEGRAL SEAT POSTS

Michael D. Helfrich, Evansville, Ind.

Application September 3, 1931, Serial No. 560,883

4 Claims. (Cl. 4—236)

This invention relates to those water closet bowls of the class having seat posts integral with the bowl.

The ordinary water closet bowl has metal posts which are secured by nuts and washers and serve as hinge posts for the seat and cover, or, for the seat alone, if no cover is used. Posts of this character are unsanitary, collect dirt, become tarnished and corrode, loosen, get out of alignment and are often the cause of breakage of the seat, cover or bowl.

Those water closet bowls of the general class to which my present improvements belong, having seat posts integral with the bowl, have generally been unsatisfactory, due to expense of manufacture, clumsy appearance, and to the fact that the integral posts project freely and are easily wrenched off by handling the seat or cover, or both, or are accidentally broken.

The principal object of the invention is to provide an improved water closet bowl having posts for the seat or seat and cover which are integral with the bowl and its shelf and are braced and reinforced by said shelf, thus eliminating all exposed metal, rubber, or fabric connections and providing a neat, sanitary construction which is strong and durable, very difficult to break and has no projecting parts.

Formed integral with the bowl and its shelf are posts extending forwardly from the shelf and provided with one or more steps according to whether a seat alone is used, a seat and cover, or a seat, cover, and "baby insert". The rear parts of the posts being integral with the shelf, they are braced and strengthened by the latter and prevented from breaking. I do not limit myself to the design or outline of the hinge posts nor to the number of steps on said posts.

The seat, and the cover, if a cover be used, have their rear parts hinged to the integral posts by rods and nuts which are concealed, leaving no projecting or exposed parts to corrode, collect dirt, or become unsanitary.

In one form of the invention, the seat and its cover have their rearwardly extending parts received between the hinged posts. In another embodiment, the rearwardly extending part of the seat straddles or receives the integral hinge posts and the cover is received between said integral hinge posts.

In that embodiment of the invention where the integral hinge posts are designed to be straddled by the seat if a cover be employed, should the installation be one such as is commonly used in hotels and other public places where no cover is

desired or necessary, that form of seat having its rear part adapted to be entered between the hinge posts may be combined therewith so that the omission of the seat cover will not result in any exposure of the hinge rod.

The seat posts integral with the bowl and its shelf, which are the principal feature of the present invention, are adapted for use in connection with low flush tanks, high flush tanks, flushometers, or any other flushing device, and I do not limit myself to the use of the bowl having improved integral seat posts in connection with any kind or type of tank or water supply or connection between the bowl and said water supply.

Among the advantages of my invention are the prevention of breakage of the integral posts while obtaining all of their advantages the elimination of exposed metal connections between the seat and its cover and the bowl; the prevention of the hinge connection working loose or getting out of alignment; the adaptability to attach the seat and cover as a unit to the bowl without the exposure of metal parts; greatly reducing the expense of the bowl, seat and cover installation because of the omission of the exposed metal hinge posts, nuts, washers and gaskets; doing away with the unsightly seat and cover connections and improving the appearance of the bowl; and other features appearing more fully hereinafter.

In the accompanying drawings:

Figure 1 is a plan view of one embodiment of the invention, the seat and cover being closed;

Fig. 2 is a side elevation thereof;

Fig. 3 is a similar view, certain parts of the bowl being broken away to show the hinged parts of the seat and cover, the hinge rods being in cross section;

Fig. 4 is a section on the line 4—4, Fig. 3;

Fig. 5 is a section on the line 5—5, Fig. 3;

Fig. 6 is a view like Fig. 1, showing a modification;

Fig. 7 is a side elevation of the modification shown in Fig. 6;

Fig. 8 is a plan view of the bowl of Figs. 1, 2, 45 and 3, the seat, cover, and hinge rods being omitted; and

Fig. 9 is a view like Fig. 8, showing the bowl of the form disclosed in Figs. 6 and 7.

Referring first to Figs. 1 to 5 inclusive and 8, 50 the bowl 1 and its shelf 1' may be of any desired construction except in respect to its hinge posts 2 which are formed integral with the bowl and its shelf, doing away entirely with exposed metal posts.

55

The hinge posts 2 which rise from the top of the bowl 1 forwardly of the shelf 1' and are integral with the bowl and shelf, are arranged parallel to each other and have one or more steps 3, 4.

5 There may be a third step, not shown, if a "baby insert" is to be used. However, it is not necessary to provide two steps, as will be apparent from the construction of the modification shown in Figs. 6, 7 and 9, where the hinge posts 2' have but a single step 5, reference to which will be made more in detail hereinafter.

10 Referring again to Figs. 1, 2, 3, 4, 5, 8, there are alined holes 6 extending through the steps 3 and alined holes 7 extending through the steps 15 4 for the reception of the hinge rods 8, 9, respectively. The hinge rods pass through the reduced rear ends 10, 11, on the cover 12 and seat 13, respectively.

15 The side faces of the rear ends 10, 11 of the cover and seat, respectively, are received snugly, yet easily, between the respective integral posts 2 and have holes 14, 15 through which the hinge rods 8, 9 loosely pass.

20 The respective hinge rods 8, 9 are held rigidly to the posts 2 by headed cylindrical internally screw threaded nuts 16, which are received in countersinks 17 in the hinge posts 2 and are provided with slots 18 so that they may be screwed up with a screw driver.

25 30 It will be observed that no metal parts of the hinge rods and nuts are exposed except the outer faces of the nuts.

35 If, with the embodiment shown in Figs. 1, 2 and 3, it is desired that the cover 12 be omitted as, for instance, in an installation in a hotel or other public place, the hinge rod 9 its nuts 16 are removed and porcelain or other studs are inserted in the countersinks 17 to close the openings in the steps 4.

40 45 Referring now to the embodiment shown in Figs. 6, 7 and 9, the seat 13 has its rearward extension cut out so that it may straddle the seat posts 2', previously referred to, instead of fitting between the seat posts. The fit of the parts, however, is close to exclude dirt.

50 The cover 12 has a down-turned part 10' on its rearward extension 10, said part fitting snugly, yet easily, between the seat posts 2'.

55 A single hinge rod, similar to the hinge rods 8, 9, extends through alined holes in the rear extension of the seat and of the cover and is secured in position by nuts 16', similar to the nuts 16.

60 65 If it is desired to dispense with the cover in the embodiment shown in Figs. 6, 7 and 9 and only to employ a seat, in that event, a seat such as shown at 13 in Figs. 1 and 2, will have its rear extension inserted between the seat posts 2' and hinged by a single hinge rod, such as either 8 or 9, and secured by nuts 16'.

70 65 In either of the embodiments disclosed, a "baby insert", not shown, may be employed, as previously explained, by substituting it for the cover 12, or, an additional step may be provided in the embodiment shown in Figs. 1 and 2 and a "baby insert" provided, thus having two seats of different sizes and one cover.

75 The bowl having the present integral seat posts may be of any material but it is particularly intended to be made of vitreous material. The hinge posts, 2, 2' being integral with the bowl 1 and shelf 1' and extending forwardly from said shelf, they are very strong and durable and

possess none of the defects incident to earlier hinge posts, which, by reason of projecting freely from the bowl, are fragile and easily wrenched or knocked off, particularly if of vitreous material.

5 What I claim is:

10 1. A water closet bowl having integral therewith a raised shelf and a pair of upstanding spaced hinge-posts integral with the bowl and raised shelf, said raised shelf joining the rear edges of the hinge-posts together and reinforcing the same, said hinge-posts being disposed within the confines of the opposite lateral side edges of the raised shelf in position to be protected thereby, and having transversely aligned holes therethrough adapted to receive a single hinge 15 rod.

20 2. A water closet bowl having integral therewith a raised shelf and a pair of upstanding spaced hinge-posts integral with the bowl and raised shelf, said raised shelf joining the rear edges of the hinge-posts together and reinforcing the same, said hinge-posts being disposed with the upper edges thereof below the top of the raised shelf and with the outermost portions of the sides thereof within the confines of the opposite lateral side edges of the raised shelf in position to be protected thereby, said hinge-posts having transversely aligned holes therethrough adapted to receive a single hinge-rod for a seat. 25

30 3. A water closet bowl having integral therewith a raised shelf and a pair of upstanding spaced hinge-posts integral with the bowl and raised shelf, said raised shelf joining the rear edges of the hinge-posts together and reinforcing the same, said hinge-posts being disposed with the upper edges thereof below the top of the raised shelf and with the outermost portions of the sides thereof within the confines of the opposite lateral side edges of the raised shelf in position to be protected thereby, and said hinge- 35 posts having transversely aligned holes therethrough adapted to receive a single hinge-rod for a seat, a seat part having a portion mounted between the hinge-posts and extending transversely from one of said posts to the other, 40 and a single hinge rod extending through the holes in the hinge-posts and through the portion of the seat part therebetween for hinging said seat part to the bowl.

45 4. A water closet bowl having integral therewith a raised shelf and a pair of upstanding spaced hinge-posts integral with the bowl and raised shelf, said raised shelf joining the rear edges of the hinge-posts together and reinforcing the same, said hinge-posts being disposed with the upper edges thereof below the top of the raised shelf and with the outermost portions of the sides thereof within the confines of the opposite lateral side edges of the raised shelf in position to be protected thereby, and said hinge-posts 50 having transversely aligned holes therethrough adapted to receive a single hinge-rod for a seat, a seat part having a portion mounted between the hinge-posts and extending transversely from one of said posts to the other, and a single hinge rod 55 extending through the holes in the hinge-posts and through the portion of the seat part therebetween for hinging said seat part to the bowl, said hinge rod terminating at the outer ends of the holes in the hinge-posts and having heads at 60 opposite ends within the confines of the outer sides of the hinge-posts.

MICHAEL D. HELFRICH.
